FUEL FEEDING SYSTEM

Edward A. Rockwell, Chicago, Ill.

Application March 3, 1930, Serial No. 432,743
Renewed June 2, 1933

5 Claims. (Cl. 123—179)

This invention relates to improvements in fuel feeding systems for internal combustion engines and more particularly to systems in which troubles due to accumulation of liquid fuel in the intake manifold are avoided and the fuel economy is maintained by preventing wastage of the excess liquid fuel which is delivered by the carburetor to the intake manifold.

It is well recognized that in general more power may be secured with down-draft carburetion than with up-draft carburetion but the use of down-draft carburetors in connection with internal combustion engines has disclosed certain difficulties in operation. If the venturi or throat of the down-draft carburetor is proportioned for maximum power at high speeds, there is so little vacuum in the venturi at low speeds when the engine is started with wide open throttle that a greater quantity of fuel must be fed than is actually utilized to give the desired mixture and, therefore, the excess liquid fuel accumulates in the lower part of the intake manifold and it has been customary to utilize a drip tube to spill out such excess liquid fuel. It is sometimes impossible to start the engine with a partially closed throttle since sufficient air is not taken in to form the fuel mixture to start the engine and flooding of the manifold takes place, as the high vacuum prevents draining through the drip tube. Furthermore, flooding of the intake manifold may occur if the vehicle is traveling at open throttle with a heavy load. It is highly desirable that some means be employed for preventing the wastage of the excess fuel which accumulates in the intake manifold. Because of the fuel wasted it has not been possible to use down-draft carburetors proportioned to give maximum power since, as the area at the throat of the carburetor is increased, more fuel is wasted on starting and while the engine is under load.

According to my previous application, Serial No. 409,538, filed November 25, 1929, I have disclosed a system for feeding fuel from the supply tank directly to the mixture chamber of a down-draft carburetor by means of a pump mechanically driven from the engine, which pump has a flexible diaphragm resiliently limited in its discharge stroke. In this previous application the fuel delivered by the pump has been further controlled by means of a pressure tube which leads from the intake manifold beyond the carburetor throttle to the backside of the flexible pumping member whereby a high vacuum in the intake manifold assists in cutting down the delivery of fuel by the pump and an opening of the throttle

resulting in substantially atmospheric pressure in the intake manifold causes an atmospheric pressure to be applied to the back side of the pump diaphragm and allows the full force of the resilient discharge means to be employed for producing a high delivery of fuel for purposes of acceleration. It is necessary in such construction to provide some means for bleeding air into the pressure tube in order to obtain the correct regulation of pressure applied to the back side of the pump diaphragm.

It is a purpose of the present invention to provide a system in which the excess liquid fuel accumulated in the intake manifold is not wasted but is returned to the carburetor and preferably the return is accomplished by sucking the excess liquid fuel into the intake side of the pump which serves to deliver fuel from the supply tank to the carburetor.

It is further an object of the present invention to trap the excess liquid fuel into a float-controlled atmospheric chamber in which a float operates upon a rise of the liquid level to open an outlet valve and a second suction-operated valve is provided which normally prevents the flow of fuel from the supply tank into the float trap chamber should the vehicle be in such position that the supply tank produces a head of fuel on the outlet from the trap chamber. The suction valve is operated by the suction of the pump to permit the fuel to be drawn out of the trap chamber and delivered to the intake side of the pump.

It is further a purpose of the present invention to combine a system for preventing wastage of the excess liquid fuel with a system such as disclosed in my previous application whereby the opening through which the excess liquid fuel is passed from the intake manifold into the trap chamber also serves as the restricted vent for bleeding air into the pressure tube which connects the intake manifold to the back side of the pump diaphragm.

Another important object of the present invention consists in improving the quick starting of engines having down-draft carburetors by requiring that the throttle be wide open when the starter is actuated. The excess fuel delivered into the carburetor throat may then flow out of the manifold or into the trap chamber since the pressure in the manifold will be substantially atmospheric. Otherwise it is apparent that the excess fuel would not flow out and the manifold would be flooded. By the use of such a system the fuel may be drained and returned to the supply line and the highest efficiency obtained.

Further and additional objects will be more readily apparent from the full description given in connection with the attached drawings in which a preferred embodiment of the invention is illustrated.

5 In the drawings:

Figure 1 is a substantially diagrammatic illustration of an internal combustion engine having the present improvements applied thereto.

10 Figure 2 is a vertical section taken through the pump which serves to deliver fuel from the supply tank to the carbureter.

15 Figure 3 is a vertical section taken through the float-controlled trap chamber and illustrating the manner in which the excess liquid fuel is delivered from the intake manifold to the trap chamber and from the trap chamber into the pipe line which leads to the intake of the pump.

20 Figure 4 is a vertical section taken through the Venturi throat of the down-draft carbureter and illustrating the arrangement of the choke and throttle valves.

25 Figure 5 is a partial diagram of the throttle linkage, and

30 Figure 6 is a partial vertical section illustrating a construction for operating the throttle linkage at the same time as the engine starter is actuated.

35 In the drawings an internal combustion engine is diagrammatically illustrated at 10, in Figure 1, and has associated therewith an intake manifold 12 for delivery of the fuel mixture into the engine cylinders. According to the preferred construction, a down-draft carbureter 14 is utilized for feeding the fuel mixture downwardly into the intake manifold but it will be apparent that certain features of the invention may be applicable to systems in which an up-draft is utilized. A fuel pump 16 is mounted on the engine casing and is mechanically driven from an engine cam shaft 40 in a well-known manner. The fuel pump serves to suck fuel through a line 18 from a supply tank 20 and deliver the fuel through a pipe line 22 which leads to the carbureter 14. The details of the carbureter are more fully described in my co-pending application, Serial No. 409,538, filed November 25, 1929, but, by referring to Figure 4, it will be understood that a vertical tube 24 is provided having at its upper end a choke valve 26 and at its lower end a throttle valve 28. A venturi 30 is provided at the mid-portion into which the fuel is directly delivered from the pipe line 22 through the central delivery orifice 32. A valve 34 closes the fuel conduit when the carbureter is inactive. Suction produced in the intake manifold 35 fold during the starting of the engine will be communicated to a diaphragm 36 which will effectuate an opening of the valve 34 against the resistance of a spring 38. The valve 34 is further intended to be controlled by a lever 40 actuated by movement of the throttle 28 whereby the valve 34 is closed when the throttle is in idle position and the fuel is then supplied through an auxiliary inlet, which is not shown in the present disclosure, and when the throttle is open wide for starting purposes, the valve 34 is opened by movement of the lever 40 in order to permit delivery of the fuel into the mixture chamber of the carbureter.

45 The construction of the fuel pump may be of any desirable form in which a substantially constant resilient pressure is maintained on the fuel delivered by the pump, and, Figure 2 illustrates a preferred construction in which the flexible pumping diaphragm 42 is positively moved in a suction direction by movement of a lever 44 actu-

5 ated from the engine cam shaft and is resiliently urged in a discharge direction to take a variable stroke by the action of the spring 46, enclosed in a chamber 48 on the back side of the pump diaphragm. The pumping chamber 50 is in communication with a fuel-receiving and trapping chamber 52 through a spring-pressed inlet valve 54. The supply line 18 from the supply tank leads into the fuel-receiving chamber 52 through a centrally disposed intake 56. The delivery 10 from the variable capacity pumping chamber 50 is through a spring-pressed discharge valve 58 into a chamber 60 from which the fuel is delivered through the pipe line 22. An air dome and vapor trap 62 is provided to maintain a uniform delivery 15 from the pump. A pressure tube 64 communicates with the intake manifold and the chamber 48, on the back side of the pump diaphragm, as shown in Figure 2, and serves to produce pressure variations in the chamber 48 corresponding to the 20 changes in pressure in the intake manifold. A plug 66 is threaded into the pump casing and has a restricted orifice 68 for bleeding air into the chamber 48 and the tube 64 is generally provided with an additional air bleed adjacent to its connection to the intake manifold.

25 The apparatus for draining the fuel from the intake manifold is shown in detail in Figure 3 in which the intake manifold is formed with a depressed trap chamber 70 which serves to collect 30 the excess liquid fuel and a threaded plug 72 is secured to the intake manifold to form the bottom of the trap chamber. A secondary trap chamber 74 is provided for receiving the fuel from the manifold trap chamber 70 and, in the disclosed 35 construction, is attached to a T-shaped head 76 inserted in the pipe line 18 which leads to the intake for the pump. A valve seat member 80 is pressed into the upward extension of the T-shaped connection 76 and cooperates with a valve 40 45 controlled by movement of a float 84 having a stem 86. The valve seat member 80 further serves as a seat for an upwardly pressed check valve 88 maintained normally in closed position by a spring 90 which is positioned by a stem 92 45 carried by a removable threaded head 94. The top of the chamber 74 is flanged, as at 96, and has seated thereon a perforated strainer plate 98 and an additional cover 100 having a flange 102. The perforated strainer 98 serves to filter 50 the air which is drawn into the intake manifold counter-current to fuel delivered into the fuel-collecting chamber 74 and tends to keep dirt out of the liquid fuel which collects in the chamber 74. The outside cover 100 and the strainer plate 98 55 are secured to the chamber 74 by means of the bolt and nut connections 104. The cover 100 has openings 106 which permit atmospheric pressure to continuously act upon the fuel in the chamber 74 and permit air to be drawn into the 60 manifold counter-current to the fuel delivered into the chamber 74. A T-shaped union 108 is threaded at its upper end into the plug 72 and extends downward into the trap chamber 74 65 through a flanged opening 110 of the outer cover 100 and an opening in the strainer plate 98. The lower end of the connection 108 has a perforated cap 112 secured thereto which forms a guide for the upper end of the float stem 86.

70 Thus the fuel from the manifold trap chamber 70 is delivered through openings 114 into the vertical passage 116 formed in the union 108 and then passes through a restricted opening 118 therein from which the fuel is delivered through the openings 120 formed in the cap 112 into the 75

chamber 122 within the trap 74. As the level of the fuel collected in the chamber 122 rises, the float valve 82 will be lifted from its seat and permit the fuel to pass in communication with the check valve 88 whereupon the suction produced in the pipe line 18 will serve to open the check valve 88 to cause the fuel collected in the chamber 122 to pass to the intake side of the pump together with the fuel from the supply tank. The fuel will be sucked out from the trap chamber until the float valve again closes, and, it will be apparent that the provision of the float valve prevents air from being drawn into the pipe line 18 which would prevent priming of the pump. Further the provision of the check valve 88 prevents fuel from being delivered into the trap chamber from the supply line 18 should the vehicle be in such position that the supply tank produces a head of fuel on the passage which leads into the trap chamber from the pipe line 18.

The restricted opening 118 formed in the duct which delivers fuel from the manifold trap to the chamber 122 prevents excessive air from being drawn into the intake manifold under vacuum conditions which might disturb the mixture of fuel and air produced by the carburetor. Another function of the restricted opening 118 consists in the fact that the opening 118 serves as an air bleed for the pressure tube which is also connected to the T-shaped union 108 by a threaded connection 124.

In starting engines provided with down-draft carburetors, it is highly desirable, in fact, almost necessary, that the throttle be moved to wide open position in order to admit sufficient air for starting purposes and to allow draining of the excess fuel. According to the present improvements, I have provided a form of linkage in which operation of the starter button causes the throttle to be immediately moved to wide open position and upon release of the starter button, the throttle is returned to the position determined by the hand throttle or foot accelerator.

In Figures 5 and 6 somewhat diagrammatic representations of the linkage are shown. 130 is a lever connected to the throttle rod 132. A bell crank lever 134 is mounted on a pivot 136 and has one arm connected by the rod 138 to the lever arm 130. The other arm of the bell crank lever 140 is connected by a rod 140 to a bell crank lever 142 having one arm 144 connected to the rod 140 and the other arm 146 connected to a rod 148 which extends to the accelerator and has a lost motion connection 150 extending to the manual throttle control. The bell crank lever 142 is pivotally mounted on a shaft 152 adjacent a pivoted lever 154 which has an extension 156 extending to come into contact with and pick up an extension 158 of the lever arm 144. The lever 154 is suitably connected by a rod 160 to be operated by movement of the starter button.

It will be apparent that any desirable connections may be employed for insuring movement of the rod 160 to effectuate an opening movement of the throttle prior to or simultaneously with the operation of the starter of the engine. In general, it will probably be desirable in cases where the starter button merely serves to close electrical contacts to have a separate lever which is given a movement prior to the operation of the starter button in order to have sufficient movement imparted to the rod 160 to move the throttle to wide open position. One form of arrangement is substantially diagrammatically illustrated in Figure 6 in which 162 is the floor board

of a vehicle having mounted thereon a switch member 164 operated by movement of the button 166 in order to close the electrical circuit indicated at 168. A bell crank pedal lever 170 is carried by a pivot 172 beneath the floor board and includes an arm 174 pivotally connected to the rod 160 while the other arm 176 of the bell crank lever extends through an aperture 178 in the floor board to a pedal portion 180 which may be actuated by the operator. The lever arm 176 includes a depending projection 182 which, upon pivotal movement of the lever 170, comes into contact with and operates the starter button 166. In order to hold the lever 170, the rod 160, and the lever arm 154 in normally inoperative position, a spring return 184 is provided connected from a fixed point 186 to the lever arm 154. The linkage by which the foot accelerator actuates the throttle may be held in released position by a spring return such as indicated at 188 connected from a fixed point 190 to the lever arm 130.

The operation of the linkage will be as follows: The operator, to start the engine, steps upon the lever 170 and during the first part of the movement the throttle of the carburetor is moved to wide open position since the movement of lever arm 154 will cause the bell crank lever 142 to be picked up and moved. During this movement the connection 150 will remain stationary together with the hand throttle usually associated with the steering wheel. As soon as the engine is started the operator releases the pressure upon the lever 170 which is thereby immediately returned by the force of the spring 184. The throttle linkage will, therefore, be returned by the spring 188 and the normal operation by the movement of the accelerator or hand throttle may take place. The advantage of such arrangement will be readily apparent since the construction absolutely insures that the throttle will be wide open when the engine is started and thereby insures atmospheric pressure in the intake manifold and therefore any excess liquid fuel which may accumulate in the intake manifold will immediately drain out into the trap chamber.

Various modifications and changes may be resorted to in the particular arrangement of the connections and parts without departing from the spirit of the invention as expressed in the appended claims.

I claim:

1. In combination with an internal combustion engine having an intake manifold, a down-draft carburetor for delivering fuel downwardly into said intake manifold, a throttle valve for controlling the mixture flow, means for draining excess liquid fuel from the intake manifold from a point on the engine side of the throttle and means for insuring the opening of the throttle valve as the engine is started to obtain substantially atmospheric pressure in the intake manifold in order to permit draining of the excess liquid fuel therefrom.

2. In combination with an internal combustion engine having an intake manifold, a down draft carburetor for delivering the fuel mixture downwardly into said manifold, a throttle valve for controlling the mixture flow, an atmospheric fuel collecting chamber, means for draining excess liquid fuel from said intake manifold from a point on the engine side of the throttle through a restricted passage into said atmospheric chamber and means for positively insuring substantially atmospheric pressure in the intake manifold

as the engine is started in order to allow flow of the excess liquid fuel from the intake manifold into said collecting chamber.

3. In combination with an internal combustion engine having an intake manifold, a down-draft carburetor for delivering the fuel mixture downwardly into the intake manifold, a throttle valve for controlling the mixture flow into said manifold, means for draining excess liquid fuel from the intake manifold from a point on the engine side of the throttle valve, means for returning the fuel drained from the intake manifold to the carburetor and means for insuring that the throttle valve is in open position as the engine is started to produce substantially atmospheric pressure in the intake manifold and permit draining of excess liquid fuel therefrom.
4. In combination with an internal combustion engine having an intake manifold, a carburetor for supplying the fuel mixture to the intake manifold, a throttle valve for controlling the flow of

the fuel mixture, means for draining excess fuel from the intake manifold from a point on the engine side of the throttle valve, starting means for the engine and means for insuring the opening of the throttle as the starting means is actuated to produce substantially atmospheric pressure in the intake manifold to permit draining of the excess liquid fuel from the intake manifold.

5. In combination with an internal combustion engine, having an intake manifold, a down-draft carburetor for delivering the fuel mixture downwardly into said intake manifold, a throttle valve for controlling the mixture flow, means for draining excess liquid fuel from the intake manifold from a point on the engine side of the throttle, starting means for the engine and means for opening the throttle as the starting means is actuated to produce substantially atmospheric pressure in the intake manifold and permit draining of the excess liquid fuel therefrom.

EDWARD A. ROCKWELL.
